ARTIFICIAL SKULL

Rudolph R. Balut, Kingston, Pa.

Application May 17, 1932. Serial No. 612,909

8 Claims. (Cl. 2—65)

This invention relates generally to animal heads, and particularly to skulls for use in connection with fur scarfs, boas, neck-pieces and the like, having for its primary object to provide an effective and realistic skull which will be strong and durable and which is so constructed as to prevent deformation of the head incident to long and extensive use.

A further object of the invention is to provide a skull of that character embodying a more or less pliant crown, and equipped with improved means for preventing crushing or deformation of the same incident to the jaw opening and closing operations.

A still further object of the invention is to provide improved means for assembling the skull and jaw clasp, and wherein the operation of assembling these elements is greatly simplified and improved and danger of the clasp becoming accidentally separated from the skull is eliminated.

With these objects in view, together with others which will appear as the description proceeds, the invention consists in the novel construction, combination and arrangement of parts, all as will be described more fully hereinafter, illustrated in the drawing and particularly pointed out in the claims.

In the drawing:—

Fig. 1 is a side elevation, parts broken away, of an artificial skull constructed in accordance with the invention,

Fig. 2 is a longitudinal sectional view taken through the skull with the mouth clasp removed,

Fig. 3 is a rear elevation of the skull,

Fig. 4 is a bottom plan view of the skull, a part being broken away,

Fig. 5 is a fragmentary bottom plan view of the skull taken substantially upon line 5—5 of Fig. 1, and

Fig. 6 is a transverse sectional view taken upon line 6—6 of Fig. 5.

Referring now more particularly to the drawing, the skull includes a relatively wide sheel or crown portion 7, from the forward end of which projects a snout portion 8 of restricted width. The rear end of the skull is preferably opened as shown. The skull is formed of relatively thin, pliable material such as rubber, but it will be understood that it may be made of other materials if so desired. The skull and the forwardly projecting snout or nose piece are made in such proportions as will be best adapted to the animal to be simulated, and it will be understood that the fur of the animal will be fitted closely upon the

skull and glass eyes inserted at the proper place near the forepart of the crown.

Associated with the skull is a clasp 9 ordinarily employed as a jaw, disposed centrally and longitudinally beneath the skull or snout piece 60 thereof. This clasp includes hingedly connected plates 10—11, the hinge pin 12 of which connects interfitting ears 13 near the rear ends of the plates, and a spring 14 associated with the hinge pin and plates normally holds the jaws of the 65 clasp in grasping position.

The plate 10 is firmly affixed to the underpart of the skull, and the snout portion is provided with a longitudinally disposed recess 15 for the snug accommodation of the plate 10. The extreme forward end of the snout on its under-surface is provided with a pocket 16 for the accommodation of the extremity of the plate, while flange portions 17 project inwardly from the sides of the snout to underlie the plate and assist in 75 retaining the same in proper position. The plate 10 is usually provided with a central longitudinal rib 18 serving as a strengthening element, and the slot or opening 19 between the flanges 17 serves to accommodate the said rib as shown in 80 Figs. 5 and 6.

The clasp extends rearwardly beyond the snout portion, and as a support for said rearwardly protruding portion, a post 20 is provided. This support constitutes a spacing element interposed 85 between the crown 7 and the plate 10, the lower or operative face of the support being disposed in substantially the same plane with the pocket 16. The said lower or operative face of the support is provided at its longitudinal edges with 90 outwardly protruding shoulders or guides 21 to prevent lateral sliding movement of the clasp plate. The support 20 is preferably formed integral with the skull and is therefore of the same material as the latter. The said support may 95 extend forwardly from its rearmost point to its juncture with the snout portion, or for the sake of economy of material, may constitute a post disposed directly above the rear portion of the clasp.

An effective means for retaining the clasp in position within the skull, and without resort to additional securing elements or means, the lateral edges of the clasp plate 10 may be serrated or toothed as at 22. These teeth may be 105 inclined in the direction of forward movement of the clasp, presenting abrupt shoulders at the rear ends of the teeth. This structure facilitates the ready application of the plate within the snout but resists rearward movement by reason 110

of the shoulders locking within the material of the snout.

With the skull and clasp constructed in accordance with the foregoing it is at once obvious that the clasp may be quickly, easily and properly inserted without the exercise of special skill or tools, and no retaining means other than the teeth 22 and the flanges 17 are required in maintaining the clasp properly positioned. When properly applied the rear portion of the clasp lies directly beneath the support or post 20, so that pressure applied to the rear end of the clasp plate 11 by grasping the skull in the hands will be resisted by the post or support 20 without possibility of collapsing or deforming the crown portion 7. The post or support 20 thus maintains the crown at all times in proper distended position, and the particular construction and assemblage prevents cocking of the clasp due to improper grasping and operation of the same.

By means of the construction and assemblage of the skull and clasp as heretofore described, it is apparent that the various objects of the invention are fully attained.

Having thus described my invention, I claim:—

1. In an animal head, a skull having a snout and a flexible crown portion, a clasp having its jaw end secured in said snout and its operating end disposed beneath said crown portion, and a support integral with said skull and interposed between said crown portion and said operating end.
2. In an animal head, a skull having snout and crown portions, said snout portion having a pocket in its under surface, a support depending from said crown portion and having its lower surface disposed in the same plane with said pocket, and a clasp having one end engaged in said pocket and its opposite end engaged with said support.

3. In an animal head, a skull having snout and crown portions, said snout portion having a pocket near its forward end, a support integral with and depending from said crown portion and having its lower surface disposed in alinement with said pocket, a clasp having its forward end engaged in said pocket and its rear end engaged with said support, and means on said support to hold said clasp against lateral movement.

4. In an animal head, a skull having a snout portion, flanges projecting inwardly from the lateral edges of said snout on the under face thereof, and a clasp having its lateral edges engaged by said flanges, said flanges overlying said edges.

5. In an animal head, a skull having a snout portion, flanges projecting inwardly from the lateral edges of said snout upon the under face thereof, a clasp plate, a rib on said plate disposed longitudinally thereof, said rib engaged by said flanges to hold the plate against lateral movement.

6. In an animal head, a skull having a snout, a pocket on the under face of said snout near the forward end thereof, flanges projecting inwardly from the lateral edges of said snout on the under face thereof, and a clasp plate having its end engaged in said pocket and its surface engaged by said flanges.

7. In an animal head, a skull having a snout, a pocket in said snout, a clasp plate, and teeth on the lateral edges of said plate to engage in the walls of said pocket.

8. In an animal head, a skull having a snout and a pliable crown portion, a clasp having its jaw portions disposed beneath said snout and its operating portion beneath said crown portion, and a substantially rigid support interposed between said crown and said operating portions.
